UNITED STATES PATENT OFFICE.

WILFORD J. HAWKINS, OF BROOKLYN, NEW YORK, ASSIGNOR TO AMERICAN MACHINE & FOUNDRY COMPANY, A CORPORATION OF NEW JERSEY.

ROTARY PUMP.

Application filed April 19, 1923. Serial No. 633,112.

To all whom it may concern:

Be it known that I, WILFORD J. HAWKINS, a citizen of the United States, residing at Brooklyn, county of Kings, and State of New York, have invented a new and useful Improvement in Rotary Pumps, of which the following is a specification.

This invention relates to an improvement in rotary pumps, and it has for its main object the production of a device of this kind which is more durable and more efficient than those heretofore in use, and capable of being run at high speed. With these and other objects not specifically mentioned in view, the invention consists in certain constructions and combinations which will be hereinafter fully described and then specifically set forth in the claims hereunto appended.

In the accompanying drawings, which form a part of this specification, and in which like characters of reference indicate the same or like parts, Fig. 1 is a central sectional view of a pump constructed in accordance with the invention; Fig. 2 is a sectional view taken on the line 2-2 in Fig. 1; Fig. 3 is a fragmentary sectional view taken on the line 3-3 in Fig. 1, but with the piston omitted; Fig. 4 is a perspective view of the piston and vane shown in Figs. 1 and 2; and Fig. 5 is a perspective view of the skew vane shown in Figs. 1, 2 and 4.

The particular device selected to illustrate the invention is but one of many possible concrete embodiments of the same. The invention therefore is not to be restricted to the precise details of the particular structure shown and described.

Referring to the drawings, 6 indicates a cylinder formed in a casing 7. This casing has a party wall 8 extending to the periphery of the cylinder and dividing an opening in the peripheral wall of the cylinder into two ports 9 and 10, one of which is a suction port and the other a delivery port. The party wall 8 is provided with a skew slot 11 open to the cylinder 6, and in this skew slot is located a skew vane 12 having a vent groove 13. The skew vane 12 slides in the skew slot 11, and as it slides outwardly it serves as an extension of the party wall 8 to always keep separate the ports 9 and 10.

The outer edge of the skew vane 12 is pivoted or hinged in a vane-retaining slot 14 formed in the periphery of an annular piston 15, parallel with its axis. The piston 15 works in the cylinder 6 by traveling in an orbital path therein. Means are provided for producing this orbital movement and this means, in the structure shown, includes a power shaft 16 having an integral eccentric within the cylinder. Ball bearings 18 are located within the piston 15 and surrounding the eccentric 17. The inner peripheries of these ball bearings are, however, larger than the eccentric 17, and for the purpose of pressing the ball bearing out of concentricity with said eccentric, there is provided a presser bar 19 within the eccentric and extending throughout its length. Springs 20 are located in pockets in the eccentric 17 and press against the bases of the pockets and against the presser bar 19. The purpose of this construction is to cause the piston 15 to bear with considerable pressure against the inner periphery of the cylinder 6 as it moves through its orbital path, and also to take up any wear that may occur on the outer periphery of the piston or inner periphery of the cylinder.

As the power shaft 16 is rotated, the piston 15 is carried through its orbital path, and the material to be pumped is sucked through one of the ports 9-10 and forced through the other. As the piston passes either of the ports 9 or 10, the radially outward thrust exerted on the piston by the springs 20-20 is resisted by the bearing of the piston on the ledges at either side of the port (see Fig. 3); and as it passes the skew slot 11, the piston rides on to the far wall of the slot before it leaves the near wall, thus eliminating the hammering action that would occur if the slot were parallel with the axis of the piston, and causing the pump to run silently.

What is claimed is:

1. In a rotary pump, the combination with a cylinder having an opening in its peripheral wall, of a piston in said cylinder, means for producing an orbital movement of said piston in said cylinder, a casing having a party wall extending to the periphery of said cylinder and dividing said opening into two ports and provided

with an internal skew slot open to said cylinder, and a skew vane hinged to said piston and working in said slot.

2. In a rotary pump, the combination 5 with a cylinder having an opening in its peripheral wall, of a piston in said cylinder, means for producing an orbital movement of said piston in said cylinder, a casing having a party wall extending to the 10 periphery of said cylinder and dividing said opening into two ports and provided with an internal skew slot open to said cylinder, and a skew vane working in said slot and hinged to said piston on a line 15 parallel with its axis.

3. In a rotary pump, the combination 20 with a cylinder having an opening in its peripheral wall, of a piston in said cylinder having a vane-retaining slot in its periphery parallel with its axis, means for producing an orbital movement of said piston in said cylinder, a casing having a party wall extending to the periphery of said cylinder and dividing said opening 25 into two ports and provided with an internal skew slot open to said cylinder, and a skew vane working in said skew slot and hinged in said vane-retaining slot.

4. In a rotary pump, the combination 30 with a cylinder having an opening in its peripheral wall, of an annular piston in said cylinder, a ball bearing within said piston, means for producing an orbital movement of said piston in said cylinder 35 including an eccentric within but smaller than the inner race of said ball bearing, means for pressing said ball bearing out of concentricity with said eccentric, a casing having a party wall extending to the periphery of said cylinder and dividing said opening 40 into two ports and provided with an internal skew slot open to said cylinder, and a skew vane working in said skew slot and hinged in 45 said vane-retaining slot.

cylinder, and a skew vane hinged to said piston and working in said slot.

5. In a rotary pump, the combination 45 with a cylinder having an opening in its peripheral wall, of an annular piston in said cylinder, a ball bearing within said piston, means for producing an orbital movement of said piston in said cylinder 50 including an eccentric within but smaller than the inner race of said ball bearing, spring actuated means within said eccentric for pressing said ball bearing out of concentricity with said eccentric, a casing 55 having a party wall extending to the periphery of said cylinder and dividing said opening into two ports and provided with an internal skew slot open to said cylinder, and a skew vane working in said 60 slot and hinged to said piston on a line parallel with its axis.

6. In a rotary pump, the combination 65 with a cylinder having an opening in its peripheral wall, of an annular piston in said cylinder having a vane-retaining slot in its periphery parallel with its axis, a ball bearing within said piston, means for producing an orbital movement of said piston in said cylinder including an eccentric 70 within but smaller than the inner race of said ball bearing, spring actuated means within said eccentric for pressing said ball bearing out of concentricity with said eccentric, a casing having a party wall extending to the periphery of said cylinder and dividing said opening into two ports and provided with an internal skew slot open to said cylinder, and a skew vane working in said skew slot and hinged in 75 said vane-retaining slot.

In testimony whereof, I have signed my name to this specification.

WILFORD J. HAWKINS.
